(57) **CLAIM**

The ornamental design for a lighter, as shown and described.

DESCRIPTION

FIG. 1 is a top, front perspective view of a lighter showing our new design.

FIG. 2 is a front elevational view thereof.

FIG. 3 is a rear elevational view thereof.

FIG. 4 is a left side elevational view thereof.

FIG. 5 is a right side elevational view thereof.

FIG. 6 is a top plan view thereof; and,

FIG. 7 is a bottom plan view thereof.

The broken line drawing of a display area and an ignition switch on the front of the lighter and the broken line drawing of a battery contact area on the rear and bottom of the lighter are for illustrative purposes only and form no part of the claimed design.
